UNITED STATES PATENT OFFICE.

CLEMENT FELTON, OF TORONTO, CANADA.

LOCK.

SPECIFICATION forming part of Letters Patent No. 443,910, dated December 30, 1890.

Application filed September 6, 1890. Serial No. 364,146. (No model.)

To all whom it may concern:

Be it known that I, CLEMENT FELTON, of the city of Toronto, in the county of York, in the Province of Ontario, Canada, have invented certain new and useful Improvements in Door-Locks, of which the following is a specification.

The object of the invention is to design a strongly-constructed, simple, and unpickable lock; and it consists in the peculiar construction, arrangement, and combinations of parts, hereinafter more particularly described, and then definitely claimed.

In the accompanying drawings, Figure 1 is an elevation of my lock with the back plate removed. Fig. 2 is a similar view with the parts in a different position. Fig. 3 is a similar view of part of the lock with the tumblers removed. Fig. 4 is a section through the line $x-x$ in Fig. 1. Fig. 5 is a section of an independent tumbler, showing also the acting part of the key. Fig. 6 is an edge view of the acting part of the key.

Referring now to the details of the drawings by letter, A represents the case, preferably struck up of sheet metal and provided with studs B C, the former having a hole which may be screw-threaded to receive a screw (not shown) for securing the plate a to inclose the works.

D is the bolt, which is preferably of T form in cross-section, whereby it is made very light yet strong. This bolt is slotted at d near one end to allow it to work over the stud C, and at its other end it is provided with a stud d' . One end of this bolt works in a T-shaped slot in the casing and its other or inner end fits in a dovetail recess in a guide E, fixed in the casing A, said inner end being shaped to correspond to the dovetail recess in the guide E.

F F indicate a series of tumblers pivoted on the stud C and having slots f in their free ends of varying shapes, but all of them showing a curved portion at right angles to the motion of the bolt and a straight portion substantially in line with the same. Each tumbler has a spring f' , preferably formed in one piece therewith, which bears against the stud B and tends to keep the tumblers down.

At G is shown a rotary barrel whose ends are shouldered to fit in the back and front

plates of the casing, and is provided with a bit g to act on the bolt D and a slit to receive the thin portion of the key, which is widened 55 at each end to receive the thicker portion of the key which turns the barrel.

The key H is made of two parts, a "shank" h and a "bit" h' , the latter being made of thin sheet metal, preferably steel, secured in 60 a slot in the former. The bit is notched in such a manner that when the key has been inserted in the barrel and then turned it raises all the tumblers F to such a position as to bring the horizontal portions of the slots f 65 into line, so that the stud d can pass into said horizontal portion of the slots.

The operation is as follows: Supposing the parts to be in the position shown in Fig. 1 and it is desired to lock the door to which the 70 lock is attached, the key is inserted in the lock as far as it will go, or until the end of the shank comes in contact with the bottom of the wide portion of the slot in the barrel G, when by turning the key the bit g passes into 75 the notch in the bottom of the bolt and moves it outward, as shown in Fig. 3, and by continuing to turn the key the bolt passes out to the full extent of its motion, as shown in Fig. 2, when the tumblers drop down, as shown 80 in said Fig. 2, and the key is still turned until the barrel assumes the position shown in Fig. 1, in which position it cannot be picked, as the opening is too small to allow of the insertion of lock-picking tools. To unlock it the 85 key is inserted, as before, and turned in the opposite direction, when the bit h' raises the tumblers, as shown in Fig. 1, in which position the horizontal slots in all the tumblers are in a line with the stud d' , as shown in 90 Fig. 4, and the bit g moves the bolt backward, and thus unlocks the lock. From this description it will be seen that I have invented a lock which is practically unpickable, and yet one that may be cheaply made and not 95 likely to get out of order, for although the bit of the key is very thin yet it is strengthened by the bit of the barrel, and as all strain of moving the bolt comes on the bit of the barrel and the shank of the key the bit of 100 the key is not likely to be damaged by wear.

What I claim as new is—

1. The combination, in a lock and with the bolt and tumblers thereof, of a barrel G, hav-

ing a bit *g*, a slit to receive the bit of the key, narrowed at one portion to fit said bit of the key and widened at another portion to receive the shank of the same, substantially as described.

5 2. The combination, with the bolt and tumblers of a lock provided with a rotary barrel, of a key having a thin portion to operate on

the tumblers and a thick portion to turn the barrel, substantially as described.

Toronto, August 2, 1890.

CLEMENT FELTON.

In presence of—

CHARLES C. BALDWIN,
F. A. WOODWARD.
